CLAIM

The ornamental design for an automatic detergent dispenser for dishwasher, as shown and described.

DESCRIPTION

FIG. 1 is a top perspective view of an automatic detergent dispenser for dishwasher, showing our new design; FIG. 2 is a bottom perspective view thereof; FIG. 3 is another bottom perspective view thereof; FIG. 4 is a front elevation view thereof; FIG. 5 is a rear elevation view thereof; FIG. 6 is a left side elevation view thereof; FIG. 7 is a right side elevation view thereof; FIG. 8 is a top plan view thereof; FIG. 9 is a bottom plan view thereof; FIG. 10 is an enlarged view taken from circled portion 10 in FIG. 1; FIG. 11 is an enlarged view taken from circled portion 11 in FIG. 1; FIG. 12 is an enlarged view taken from circled portion 12 in FIG. 1; FIG. 13 is another top perspective view of thereof, shown in an alternative state of use; and, FIG. 14 is an enlarged view taken from circled portion 14 in FIG. 13.

The dash-dash broken lines shown in the drawings depict portions of the automatic detergent dispenser for dishwasher that form no part of the claimed design.

The dot-dash lines illustrate the boundary of the enlarged views and form no part of the claimed design.
